RAFTER FOR GREENHOUSES, ETC

Filed May 9, 1930

P. E. George
INVENTOR
BY Victor J. Evans
ATTORNEY

UNITED STATES PATENT OFFICE

PHILIP E. GEORGE, OF SOUTH FORK, PENNSYLVANIA

RAFTER FOR GREENHOUSES, ETC.

Application filed May 9, 1930. Serial No. 451,112.

This invention relates to roof construction and more particularly to those forms of roofs for hot houses, galleries and conservatories, etc., where the major portion of the roofing is composed of window panes and the like.

One of the principal objects of the invention embodies the arrangement of supports for the window panes.

Another object of the invention consists in the provision and arrangement of valleys or gutters in the support to relieve condensation between the supports and window panes.

An additional object of the invention consists of parting strips for the supports having connection with the window panes in the conventional manner.

With the above and other objects in view, the invention further consists of the following novel features and details of construction, to be hereinafter more fully described, illustrated in the accompany drawing and pointed out in the appended claims.

In the drawing:

Figure 1 is a fragmentary side elevation of my improved form of roof construction.

Figure 2 is a sectional view taken on line 2—2 of Figure 1.

Figure 3 is a sectional view taken on line 3—3 of Figure 1.

Referring to the drawing in detail wherein like characters of reference denote corresponding parts, the reference character 10 indicates generally a conventional form of metallic grating of T-shape cross section generally employed in the building of hot house roofs and against which the transparent window lights or panes repose.

It has been found that this method of roof construction is faulty in several respects. Due to the fact that glass and metal have different coefficients of expansion, the customary seals, established therebetween by putty and glazier's points, are destroyed, permitting ingress of rain, melting snow and the like and the glass panes themselves become moist upon the under sides thereof due to the radical difference of temperature upon opposite sides thereof.

To avoid all of these difficulties, as heretofore experienced, I provide rafters 11 which

are supported upon the outermost flat surfaces of the T-shaped metallic rafters 10. The upper sides of the rafters 10 are grooved to provide longitudinal V-shaped troughs or gutters 12 having a coating of roofing cement 12' to adhesively secure lengths of roofing paper or other water proof material indicated at 13. Parting strips 14 are then secured upon the upper side of the roofing paper 13 centrally and longitudinally of the apex of the V-shaped valleys or gutters 12 in the manner suggested in Figure 3 of the drawing by nails or other fastenings. The window panes or lights 15 are then laid upon the roofing paper 13, between the parting strips 14 65 and overlapped at their upper and lower ends. Putty and glazier's points are then employed between the outermost and adjacent portions of the window panes and parting strips. In this manner the metal roof substructure will 70 be separated or otherwise insulated from the window lights and any condensation forming upon the under surface of the window lights above the roofing paper 13 and dropped thereon will flow downwardly through the 75 valleys or gutters and obviate deterioration of the roofing construction incident to the maintenance of moisture deposits.

The invention is susceptible of various changes in its form, proportions and minor 80 details of construction, and the right is herein reserved to make such changes as properly fall within the scope of the appended claims.

Having described the invention, what is claimed is:

1. A roof construction comprising rafters having open gutters in the uppermost exposed portions thereof and extended rectilinearly thereof, parting strips carried by the rafters centrally of the gutters and spaced from the median portion of the latter, and roof coverings abutting opposite sides of the parting strips and spaced from the gutters to facilitate the catching and carrying off of condensation dropping therefrom.

2. A roof construction comprising rafters having gutters in the uppermost exposed portions thereof and extended rectilinearly thereof, a facing for the gutters, parting strips disposed centrally of the gutters and sup-

ported thereby upon opposite sides of the median center thereof, and roof coverings abutting opposite sides of the parting strips and spaced from the gutters to facilitate the catching and carrying off of condensation dropping therefrom.

3. A green-house roof structure comprising rafters having longitudinal gutters V-shaped in the cross sections in the upper sides thereof, facings or paper for the gutters, rectangular parting strips having their under sides extending across the gutters and spaced from the median center thereof and bearing at end edges upon the paper, and rafter sections bearing upon the paper at the side edges of the gutters and abutting with vertical sides of the parting strips.

In testimony whereof I affix my signature.

PHILIP E. GEORGE.
